UNITED STATES PATENT OFFICE

169,794

CABINET TABLE

Harry R. Trout and Frederick M. Hill, Pittsburgh,
Pa., assignors to American Radiator & Standard
Sanitary Corporation, Pittsburgh, Pa., a
corporation of Delaware

Application January 2, 1953, Serial No. 22,972

Term of patent 14 years

(Cl. D33—7)

To all whom it may concern:

Be it known that we, Harry R. Trout and Frederick M. Hill, citizens of the United States, residing at Pittsburgh, State of Pennsylvania, have invented a new, original, and ornamental Design for a Cabinet Table, of which the following is a specification, reference being had to the accompanying drawing, forming a part hereof.

The figure is a perspective view showing one side and the front of the cabinet table, embodying our new design.

We claim:

The ornamental design for a cabinet table, substantially as shown.

HARRY R. TROUT.
FREDERICK M. HILL.
